US0D1010255S

(12) **United States Design Patent** (10) **Patent No.:** **US D1,010,255 S**
(45) **Date of Patent:** **** Jan. 2, 2024**

(54) **SHOES CARE MACHINE FOR VEHICLES**

(71) Applicant: **LG ELECTRONICS INC.**, Seoul (KR)

(72) Inventors: **Seunghyun Ji**, Seoul (KR); **Dongeun Kim**, Seoul (KR); **Hyunjin Yoon**, Seoul (KR); **Euisseok Lee**, Seoul (KR); **Jaebboom Im**, Seoul (KR); **Sanghyun Choi**, Seoul (KR); **Mujin Park**, Seoul (KR)

(73) Assignee: **LG ELECTRONICS INC.**, Seoul (KR)

(**) Term: **15 Years**

(21) Appl. No.: **29/818,821**

(22) Filed: **Dec. 10, 2021**

(30) **Foreign Application Priority Data**

Nov. 11, 2021 (KR) 30-2021-0053722

(51) **LOC (14) Cl.** **15-05**

(52) **U.S. Cl.**

USPC **D32/8**

(58) **Field of Classification Search**

(57) **CLAIM**

The ornamental design for a shoes care machine for vehicles, as shown and described.

DESCRIPTION

FIG. 1 is a front, right side, perspective view of a shoes care machine for vehicles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reference view thereof;

FIG. 9 is a reference view thereof; and,

FIG. 10 is a reference view.

The broken lines indicate portions of the article that form no part of the claimed design. The broken lines in FIGS. 8, 9 and 10 depict environment subject matter and form no part of the claimed design.

1 Claim, 7 Drawing Sheets
